COMPLEXION COLOR MEASURING DEVICE

Robert C. Dorr, Woodland Hills, Calif., assignor to
Ameritone Color Key Corporation, Compton, Calif.

Filed June 9, 1969, Ser. No. 17,606

Term of patent 14 years

Int. Cl. D10—99; D28—02

U.S. Cl. D52—6

FIG. 1 is a front elevational view of a complexion color measuring device showing my new design;

FIG. 2 is a side elevational view;

FIG. 3 is a rear elevational view; and

FIG. 4 is a top plan view.

The variations in density of stippling indicate variations in hue and intensity.

I claim:

The ornamental design for a complexion color measuring device, substantially as shown and described.
